US0D1063413S

(12) **United States Design Patent** (10) **Patent No.:** **US D1,063,413 S**
(45) **Date of Patent:** **** Feb. 25, 2025**

(54) **SCREEN**

(71) Applicant: **Knoll, Inc.**, East Greenville, PA (US)

(72) Inventor: **Daniel Grabowski**, East Grand Rapids, MI (US)

(73) Assignee: **Knoll, Inc.**, East Greenville, PA (US)

(**) Term: **15 Years**

(21) Appl. No.: **29/864,620**

(22) Filed: **Jun. 8, 2022**

(51) **LOC (15) Cl.** **06-06**

(52) **U.S. Cl.** **D6/332**
USPC **D6/332**

(58) **Field of Classification Search**

(57) **CLAIM**

The ornamental design for a screen, as shown and described.

DESCRIPTION

FIG. 1 is a perspective view of the first embodiment of a screen, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view of the second embodiment of a screen;

FIG. 9 is a front elevational view thereof;

FIG. 10 is a rear elevational view thereof;

FIG. 11 is a top plan view thereof;

FIG. 12 is a bottom plan view thereof;

FIG. 13 is a left side elevational view thereof;

FIG. 14 is a right side elevational view thereof;

FIG. 15 is a perspective view of the third embodiment of a screen;

FIG. 16 is a front elevational view thereof;

FIG. 17 is a rear elevational view thereof;

FIG. 18 is a top plan view thereof;

FIG. 19 is a bottom plan view thereof;

FIG. 20 is a left side elevational view thereof; and,

FIG. 21 is a right side elevational view thereof.

The broken lines shown in the drawing Figures illustrate portions of the screen that form no part of the claimed design.

1 Claim, 15 Drawing Sheets
